UNITED STATES PATENT OFFICE.

HERMAN F. BUSCH, OF MILLVALE, PENNSYLVANIA, ASSIGNOR TO ARMSTRONG CORK COMPANY, OF PITTSBURGH, PENNSYLVANIA, A CORPORATION OF PENNSYLVANIA.

CORK SEAL FOR BOTTLE-STOPPERS AND THE LIKE AND METHOD OF MAKING THE SAME.

1,131,326.

Specification of Letters Patent.

Patented Mar. 9, 1915.

Application filed July 29, 1914. Serial No. 853,978.

To all whom it may concern:

Be it known that I, HERMAN F. BUSCH, a citizen of the United States, residing at Millvale, in the county of Allegheny and 5 State of Pennsylvania, have invented new and useful Cork Seals for Bottle-Stoppers and the like and Methods of Making the Same, of which the following is a full, clear, and exact description, reference being had 10 to the accompanying drawings, forming part of this specification, in which—

Figure 1 is a section through a crown bottle stopper having one of my seals or washers applied thereto. Fig. 2 is a sectional 15 view of the washer or seal on a larger scale, and Fig. 3 is a plan view showing a defective washer member.

In the manufacture of natural cork disks or washers for bottle stoppers and the like 20 of the well known crown type, the usual method is to cut the disks or washers of full thickness from cork wood. In this operation, the waste is usually from eighty to ninety per cent.; and a large percentage of 25 this waste is due to the fact that many of the cut washers or disks are too imperfect or defective to admit of their use by reason of holes, cracks, or pits therein. In fact, with cork wood of a relatively inferior character 30 it is frequently the case that the number of defective disks or washers cut therefrom will exceed the number of good washers obtained.

My invention is designed to provide a 35 method in which this waste may be very greatly reduced, by utilizing the defective cuttings as well as the good cuttings in the manufacture of the finished seals or washers.

In the practice of my invention, the cork 40 wood is cut in the same manner as heretofore, but instead of making the cuttings the full thickness of the finished seal or washer, they are cut to about one-half of the finished thickness. That is to say, if the 45 finished seal or washer is to be one-tenth of an inch in thickness, I make the cuttings about one-twentieth of an inch in thickness. The cuttings are then sorted in two different 50 classes, the good cuttings being put in one class and the inferior or defective ones in a separate class. The finished seals or washers are then made by assembling or uniting one good cutting and one defective cutting by means of a suitable adhesive. This gives

a finished washer which is capable of meeting all the requirements, since the defective or inferior portion thereof is thoroughly protected by the portion thereof of better quality, as well as by the interposed adhesive. 55

The assembling of the two portions of the washers is preferably carried out at the time the washers are inserted into the metal shell of the bottle crown or cap. This may be readily done by existing assembling machines such as are well known in the art, with slight modifications, consisting in the use of two cork feeders, one for each grade or class of cork cuttings, and the provision of additional adhesive supplying means. 60 For instance, the interior of the metal shell 2 of the crown may be first supplied with adhesive, either in the form of the usual paper collet, or in any other desired form; an inferior cork disk 3 may then be fed 65 into the shell in the usual way. Additional adhesive 4 is then applied to the surface of this disk, either in the form of another adhesive paper collet, or otherwise; and a cork cutting 5 of the better quality then applied 70 from another feeder, and the parts forced together by a plunger in the usual way. While this operation will slightly increase the cost of assembling the crowns, this increase in cost will be more than compensated 75 for by the saving in cork material, since the practice of my invention will enable the production of about twice as many completed seals or washers from a given amount of cork wood as has heretofore been possible. 80

I prefer to unite the two disks or washers by means of an intermediate adhesive paper collet as a finished seal having this intermediate paper layer between its cork members possesses an important advantage. 85 While that part of the finished seal which comes next to the liquid contents of the bottle is in all cases designed to be of first class cork material, free from holes, it may sometimes happen that a defective piece of cork 90 will be used. In such cases, the interposed paper collet acts effectively as a seal between the two cork members so that there can be no leakage entirely through the seal. Furthermore, when the seal is compressed upon 95 the mouth of the bottle, the flexible intermediate paper layer will readily yield to the compression of the cork. The use of an 100 105

interposed paper layer also enables compound sheets, composed of two grades of cork to be made up in any desired size, and the completed seals subsequently cut therefrom.

While my invention is particularly applicable to and valuable in connection with the manufacture of crown corks and seals, it may be applied to the manufacture of 10 other cork washers.

I claim:

1. The herein described method of making a compound cork article, which consists in uniting a piece of inferior cork material 15 and a piece of better grade cork material by

means of an interposed layer of adhesive paper, substantially as described.

2. A new article of manufacture, consisting of a cork layer of high grade material, and another cork layer of inferior quality 20 united to the first named layer by an interposed layer of adhesive paper, substantially as described.

In testimony whereof, I have hereunto set my hand.

HERMAN F. BUSCH.
